CLAIM

The ornamental design for a media center home control system, as shown and described.

DESCRIPTION

FIG. 1 is a right, front perspective view of the media center home control system, showing our new design;

FIG. 2 is a front view thereof;

FIG. 3 is a back view thereof;

FIG. 4 is a right view thereof;

FIG. 5 is a left view thereof;

FIG. 6 is a top view thereof;

FIG. 7 is a bottom view thereof;

FIG. 8 is a front view of the detachable remote control portion of the invention shown in FIG. 1, shown separately for clarity and visibility of its surfaces;

FIG. 9 is a back view thereof;

FIG. 10 is a top view thereof;

FIG. 11 is a bottom view thereof;

FIG. 12 is a right side view thereof;

FIG. 13 is a left side view thereof;

FIG. 14 is a front view of the docking station portion of the invention shown in FIG. 1, shown separately for clarity and visibility of its surfaces;

FIG. 15 is a back view thereof;

FIG. 16 is a right side view thereof;

FIG. 17 is a left side view thereof;

FIG. 18 is a top view thereof; and,

FIG. 19 is a bottom view thereof.
